THERMAL INSULATING BUILDING UNIT

Edward L. Benedict, New York, N. Y., assignor
to Elb Products, Inc., New York, N. Y., a corporation of New York

Application October 21, 1936, Serial No. 106,709

7 Claims. (Cl. 154—45)

This invention relates to thermal-insulating building units, that is to means for thermally insulating structures of all sorts such as houses, ships and the like, and has for its object to provide a unit for such use which is easier to handle and place in position as well as easier to ship than are the present thermal insulating units.

One objection to the use of metal foil has been the inconvenience in handling and shipping it or else the inconvenience in inserting it. One suggestion contemplated the foil being attached to a foundation for giving it strength. If the foundation is rigid and easy to insert between studs, beams or other framing members, it is not convenient for shipment. On the other hand, if the foil is mounted on paper and made easy for shipment in rolls, considerable labor expense is required to properly space and mount the foil sheets between the framing members.

It has been customary to crumple up foil sheets and mount them between the framing members. The objection to this practice is that the spacing and therefore the efficiency of the spaced foils will not be uniform and in fact there is not enough certainty that the foils will be spaced apart everywhere. Metal foil is so light and thin and easily torn that its insertion in a building has not been considered altogether easy.

Under this invention metal foils are mounted in pairs with an intermediate foundation and the unit being constructed so that it is easier to assemble and insert in place, yet unusually well adapted for shipment without danger of being torn.

35 Referring to the drawing

Fig. 1 shows a folded insulating unit according to this invention.

Fig. 2 is the unit of Fig. 1 partially expanded.

Fig. 3 shows the unit of Fig. 1 fully expanded and placed in position between studs or framing members.

Fig. 4 shows how the unit of Fig. 1 when made in substantial lengths can be folded transversely for compactness in shipping.

45 Fig. 5 shows the manner of inserting the thermal-insulating unit of this invention beneath the floor boards.

Fig. 6 shows another embodiment of this invention.

50 As shown in Fig. 3, between studs, beams or framing members 10 and 11 is mounted the thermal-insulating unit 12 of this invention. This unit comprises an accordion plaited foundation 13 having the plaits arranged longitudinally of the unit and spacing layers of metal foil 14 and 15

attached to the foundation. The foundation 13 may be of paper, preferably about a seventy pound paper (that is, a ream of sheets 24" by 36" weighs 70 lbs.) although heavy metal foil or a metal foil mounted on paper might be used, or 5 where fireproof construction is desired an asbestos or other fireproof paper is suitable. The metal foil layers 14 and 15 are preferably aluminum foil about .0003 inch thick although the foil of other metals may be used, the aluminum foil 10 being preferable.

The foil layer on each side of the foundation may be of the same width or, if desired, the foil on one side of the foundation may be folded around the projecting end 18 of the foundation as 15 shown in Fig. 3 and a nail, tack or other securing means passed through the folded foil and foundation to secure the same to a framing member. In the embodiment illustrated it will be seen that the foil layer 14 is not as long as is the 20 foil layer 15, the foil layer 14 terminating at 16 adjacent to the framing member and the last fold or crease 17 in the plaited foundation. The unit illustrated is expandable and compressible so that it is adapted for variations in the framing members. 25

In the position shown in Fig. 3 the unit is substantially fully expanded so that the foils limit further expansion of the accordion plaited foundation 13. Should the framing members 10 and 30 11 be located slightly further apart than as shown in Fig. 3 the ends 18 of the foundation are capable of being bent if necessary in an additional place near the tacks 19. When the framing members are much closer together the unit will be 35 partially compressed and appear more nearly like the construction illustrated in Fig. 2. When fully compressed laterally of the plaited the compact unit is of the appearance shown in Fig. 1. These units are preferably of customary length between 40 fire stops when adapted for insertion between the wall studs. Where adapted for insertion beneath the flooring these building units may be as long as the beams.

In order to make these units adapted for shipping in shorter lengths the elongated compressed unit 20 shown in Fig. 1 is folded transversely as often as is desired to make a compact bundle 21 for shipment as shown in Fig. 4.

Where the insulating unit of this invention is 50 to be applied beneath an existing floor 24 it will be found desirable to take up conveniently spaced floor boards leaving the spaces 22 and 23 as shown in Fig. 5. The unit of Fig. 1 can then be bent and inserted beneath the floor when ar- 55

ranged on its side as shown. After the unit has been extended throughout the full length of the floor beams it may be turned 90° and laterally expanded to fill the space between the beams or 5 framing members 10a and 11a and then secured to these beams in a similar manner to that shown in Fig. 3 with the plaits of the foundation running in a direction across the floor boards.

An advantage in this construction is that the 10 floor boards need not all be taken up but only certain ones and just enough to enable the unit of Fig. 1 to be pulled through beneath the floor.

In Fig. 6 is shown a modification of this invention using three instead of two spaced layers of foils. In constructing the device shown in Fig. 6 the inner foil layer 14a will be inserted between the plaited foundations 13a and 13b, the inner foil layer being attached to the plaited foundations either by means of a flexible adhesive or 15 by means of stitching. After the two plaited foundations and the inner foil layer have been secured together the outer foil layers 15a and 15b are then attached preferably by adhesive.

Among the advantages of this invention may 20 be mentioned the lightness in weight whereby an efficient thermal-insulating building unit may be provided which occupies only a very small portion of the space occupied by other thermal-insulating material of equal effect. The building unit 25 of this invention is also very light and still more important is adapted for shipment by being folded compactly. The ease with which this building unit may be expanded from its collapsed or shipping position and placed in position is 30 another important advantage. There is a breathing space between the foils eliminating any tendency for sweating or the formation of condensed moisture. This elimination of condensation and sweating precludes danger of rot taking 35 place in wood framing members and fire stops. It is known that two sheets of window glass spaced apart reduce the tendency for moisture to be deposited on either and this same principle applies to the thermal-insulating building unit 40 of this invention. There are provided partitions between the foil layers which reduce the tendency for convection currents to take place in any but a generally vertical direction.

In the embodiment illustrated in Fig. 3 any 45 rising currents of air in one cell are substantially out of contact with similar currents of air in an adjacent cell and also are out of contact with the opposite foil layer so that if the foils are different temperatures there is little likelihood of heat 50 transfer between them by convection.

The foundation is preferably non-metallic although it may be metal foil somewhat heavier than the foil layers which are spaced apart by the foundation. If desired some other insulating material than the aluminum foil referred to may be substituted on one or both sides of the foundation.

Substantially similar constructions formed of heavier material are appropriate for use as fire 65 doors, curtains, etc. although in the heavier constructions the foundation slat-like portions need not necessarily be integral but may be hinged or pivotally secured together as may also the covering slat-like portions. The foils may be attached to the foundations as illustrated by either adhesive or stitching.

In place of the foil layers 14 and 15 it will be understood that foil mounted on paper may be used. It is believed the added efficiency from the 70 use of three layers of foil instead of two is not

large enough to warrant the construction of Fig. 6 being extensively used. A simpler three foil layer construction would result from having the foundation 13 of Fig. 3 coated on one or both sides with foil. 5

It has been estimated by one contractor and builder that the units of this invention may be put in place at about one fourth the labor cost of applying spaced crumpled foils now in use. In applying such crumpled foils it is customary to 10 place a fibrous strip between the foils and the heads of the tacks or other fastening means to keep the foils from being torn.

In this invention the edge of the fibrous foundation serves as such protecting strip. 15

As used in the appended claims, the term "wall" includes a floor as well as a wall.

I claim:

1. A thermal insulating unit comprising an accordian-plaited-like foundation having the ability 20 to be expanded and contracted laterally and comprising a series of slat-like portions connected together so that on expansion or contraction a hinge-like movement occurs at the connections of said slat-like portions, and a heat reflective metal 25 accordian-plaited-like covering for said foundation on at least one side thereof, said covering also including slat-like portions of less width than those of the foundation and attached by hinge-like connections to said foundation at at least 30 some of said hinge-like portions thereof on at least one side.

2. A thermal insulating unit comprising an accordian plaited foundation having on at least one 35 side thereof an accordian plaited layer of fragile foil material having its plaita of less depth than those of the foundation and attached and positively secured to the foundation along at least some of the vertices of the foundation, each side of said unit being expansible and compressible 40 laterally of the plaita, air cells being formed on at least one side of the foundation when expanded.

3. A thermal insulating unit comprising an accordian plaited foundation having on at least one 45 side thereof an accordian plaited layer of metal foil having its plaita of less depth than those of the foundation, attached to and positively secured to the foundation along at least some of the vertices of the foundation, said foundation on each 50 side being expansible and compressible laterally of the plaita, and a second layer of metal foil having its plaita also of less depth than those of the foundation and positively secured to the foundation along at least some of the vertices on the 55 opposite side of the foundation from said first layer of foil, whereby the foil layers are maintained in spaced relation when the foundation is at least partially expanded, at least one of the foil layers being adapted to limit lateral expansion of 60 the foundation and said foundation being of non-metallic thermal insulating material, air cells being formed on both sides of said foundation when expanded.

4. A thermal insulating unit comprising an accordian plaited foundation having on at least one 65 side thereof an accordian plaited layer of metal foil having its plaita of less depth than those of the foundation, attached to and positively secured to the foundation along at least some of the vertices of the foundation, said foundation on each 70 side being expansible and compressible laterally of the plaita, said unit when compressed laterally being foldable longitudinally for compactness in shipment. 75

5. A building wall having an air space between framing members, a thermal insulating unit secured in said space and held by said framing members in spaced relation to any covering for said framing members whereby an air space is provided on each side of said unit, said unit including an accordion plaited foundation having on each side thereof a plaited layer of metal foil positively secured along at least some of the vertices of the foundation, said unit being constructed to be expandible and compressible for shipment and before being attached in position, the foil layer on each side having its plaits of less depth than those of the foundation whereby the space between the foil layers on opposite sides of the foundation is divided by the foundation into a number of air cells, each of which has two of its walls constituted by the foundation plaits.
6. A thermal insulating unit comprising spaced layers of metal foil each folded by being creased in substantially alternate directions longitudinally, and a non-metallic foundation of thermal insulating material also folded by creasing in substantially alternate directions longitudinally and having at least two of its folds attached to and positively secured for a substantial portion of their length to one of the foil layers adjacent folds in the foil, at least two other foundation

5 folds on the opposite side being similarly secured to the opposite foil layer, at least some of the folds in the foundation being spaced apart a substantially greater amount than are the foil folds whereby the foundation effects a spacing of the 10 foil layers when either compressed or expanded, the foils and the foundation together being adapted to be expanded and compressed laterally of the folds on each side of the foundation, and the foil layers being adapted to limit lateral expansion of the foundation and form air cells on both sides of the foundation when expanded.

7. A thermal insulating unit comprising an accordion plaited foundation having on at least one side thereof an accordion plaited layer of flexible 15 metal foil material which has its plaits of less depth than those of the foundation and which is attached to and positively secured to the foundation longitudinally and adjacent at least some of the vertices, each side of the unit, that is front 20 and back, being expandible laterally of the plait from compressed position, and the said layer of flexible metal foil material limiting the lateral expansibility of the foundation between at least the secured together proportions of the foundation 25 and flexible foil material to form air cells between the foil material and foundation when expanded.
